UNITED STATES PATENT OFFICE.

ERNST H. HUENEFELD, OF CINCINNATI, OHIO.

DESIGN FOR A HEATING-STOVE.

SPECIFICATION forming part of Design No. 30,963, dated June 6, 1899.

Application filed May 3, 1899. Serial No. 715,485. Term of patent 14 years.

To all whom it may concern:

Be it known that I, ERNST H. HUENEFELD, of Cincinnati, in the county of Hamilton and State of Ohio, have invented a new and original Design for Heating-Stoves, of which the following is a full, clear, and exact description, reference being had to the accompanying drawings, forming a part thereof.

In the accompanying drawings, Figure 1 is a view in side elevation of a stove embodying my design. Fig. 2 is a view in plan.

The leading and important feature of my design consists of a stove-body rectangular vertically both in front and side elevation and angular horizontally. The corners of the body instead of being sharp right angles are curved, as shown, and located at the lower ends of the corners are the legs, the upper

ends of which overlap the outside lower edges of the body.

A represents the rectangular body, and B the legs or supports located at the corners and overlapping the lower edges of the body, as shown at C.

The body is provided on its front with an angular frame D, projecting slightly from the front face of said body, and is also provided on its top near its front edge with a cylindrical collar E, surmounted by a conical cap F.

What I claim is—

The design for a heating-stove herein shown and described.

ERNST H. HUENEFELD.
